DESIGN FOR A LENS STRAP

Samuel E. Bouchard, Rochester, N. Y., assignor
to Bausch & Lomb Optical Company, Rochester, N. Y., a corporation of New York

Application February 25, 1936, Serial No. 61,340

Term of patent 7 years

To all whom it may concern:

Be it known that I, Samuel E. Bouchard, a citizen of the United States and a resident of Rochester, county of Monroe and State of New York, have invented a new, original, and ornamental Design for Lens Strap, of which the following is a specification, reference being had to the accompanying drawing, forming a part thereof.

Fig. 1 is a side elevation of a lens strap showing my new design.

Fig. 2 is a top plan view of same.

I claim:

The ornamental design for a lens strap, as shown.

SAMUEL E. BOUCHARD.
